(57) **CLAIM**

The ornamental design for makeup eyeglasses, as shown and described.

DESCRIPTION

FIG. 1 is a top plan view of the makeup eyeglasses according to the invention.

FIG. 2 is a front view thereof.

FIG. 3 is a right side view thereof, the left side being a mirror image thereof; and,

FIG. 4 is a bottom plan view thereof.

The broken lines are for environmental purposes only and form no part of the claimed design.

1 Claim, 2 Drawing Sheets

FIG. 3

FIG. 4
